UNITED STATES PATENT OFFICE.

MAUDE SINCLAIR GEORGE, OF ST. LOUIS, MISSOURI.

DESIGN FOR A GARMENT-PROTECTOR.

59,736.

Specification for Design.

Patented Nov. 22, 1921.

Application filed May 23, 1921. Serial No. 471,976. Term of patent 14 years.

To all whom it may concern:

Be it known that I, MAUDE SINCLAIR GEORGE, a citizen of the United States of America, residing at St. Louis, in the county of St. Louis and State of Missouri, have invented a new, original, and ornamental Design for Garment-Protectors, of which the following is a specification, reference being had to the accompanying drawings, forming a part thereof.

Fig. 2 is a fragmentary enlarged detail view of the outer surface of the edge portion of the protector showing in detail the character of the ornamentation, and

Fig. 3 is a view similar to Fig. 2 but of the inner side of the edge of the protector.

What is claimed is:

The ornamental design for a garment protector, as shown in the drawing.

MAUDE SINCLAIR GEORGE.
